UNITED STATES PATENT OFFICE.

JAMES W. WOOLLEY, OF DENVER, COLORADO.

VICTORIA AND BUGGY TOP.

No. 906,352.

Specification of Letters Patent.

Patented Dec. 8, 1908.

Application filed November 16, 1907. Serial No. 402,483.

To all whom it may concern:

Be it known that I, JAMES W. WOOLLEY, a citizen of the United States, residing at Denver, in the county of Denver and State of Colorado, have invented new and useful Improvements in Victoria and Buggy Tops, of which the following is a specification.

This invention relates to vehicle tops and more particularly to the slat irons connecting the bows of said tops, and the object of the invention is to provide a vehicle having a closed top with bows provided with slat irons arranged in such a pivotal connection with each other to insure relatively different lengths when the top is lowered and when the top is raised, so that a covering and a lining therefor may be secured upon the bows when in their raised position and not be torn or stretched out of position upon the bows when the top is lowered.

With these and other objects in view the invention resides in the novel construction and arrangement of parts hereinafter fully described and claimed.

In the accompanying drawings, Figure 1 is a side elevation of a vehicle illustrating my improved top arranged thereon, the covering being shown in the dotted lines. Fig. 2 is a similar view, the bows of the top being illustrated in their lowered position. Fig. 3 is an enlarged detail elevation illustrating the pivotal connection of the slat irons. Fig. 4 is a detail perspective view of an ordinary goose neck for vehicle bodies employed in connection with the present invention.

In what is commonly termed "close work" by the trade, the inner and outer covering comprising the top of a vehicle have their top and side portions each cut from a single piece of material, and the bows and slat irons supporting the top are each pivotally connected with the goose neck of the vehicle body. The top of the covering is arranged in the form of a bow, and to attain this shape the bows supporting the covering are each arranged at a different length from their pivotal point. With this arrangement, it will be noted, when the covering is lowered, the bows being of different lengths, each describe a different arc from their pivot point when the top is lowered, thus forcing the sides of the covering to undergo a severe strain at their point of connection with the

slat irons, which frequently results in the tearing of the covering or lining or both.

In the accompanying drawings, I have illustrated a construction of slat irons for the bows of the tops adapted to be used in connection with closed coverings which are so arranged and pivoted as to impart a downward and a forward movement to the front and rear irons when the top is lowered, thus producing a slack which will entirely obviate the liability of tearing and creasing the cover, and at the same time tending to draw the top forward upon the body support, and reducing the extended portion of the top beyond the rear of the body thereby lessening the weight of this projecting portion and obviating the liability of bending of the projecting portions of the bows supporting the cover.

In the accompanying drawing the numeral 1 designates a vehicle body of any ordinary or preferred construction and being provided with the usual goose neck 2, adapted for pivotal connection with the slat iron 3 of the intermediate bow 4 of the carriage top. The bow 4 is of lesser length than the front bow 5 and the rear bow 6, and the slat iron 3 of the intermediate bow is provided with a rearwardly extending portion or finger 7. The extension 7 is provided with a suitable perforation or opening which is adapted for the reception of a pin or pintle 8, by which the slat iron 9 of the rear bow 6 and the slat iron 10 of the front bow 5 are pivotally connected with the extension 7 of the iron 3. It will be noted by reference to the accompanying drawings that the slat iron 10 of the front bow 5 extends rearwardly from the body of the iron at a suitable inclination or curve to its point of connection with the extension 7 of the iron 3.

From the above description, taken in connection with the accompanying drawings it will be noted that when the top of the vehicle is lowered the middle bow 4 will swing upon its pivotal connection with the goose neck 2, forcing the rear bow 6 and front bow 5 downwardly through the medium of the projecting finger 7, and as the top is lowered the bows 5 and 6 will be drawn inwardly thus allowing a lesser projection of the vehicle top beyond the rear of the body and thereby reducing the liability of bending of the projecting bows.

It will be noted that when a closed vehicle top provided with the present improvements is lowered the strain upon the covering is entirely overcome and the liability of tearing or creasing the top effectively obviated.

Having thus fully described the invention what is claimed as new is:

A vehicle top having supporting bows, the intermediate bow being pivotally connected 10 with the body of the vehicle and being provided with a rearwardly extending portion, the rear bow pivotally connected with this

projection, and the front bow being provided with a rounded and upwardly inclined extension and said extension being pivotally connected with the rear bow and the extending portion of the intermediate bow.

In testimony whereof I affix my signature in presence of two witnesses.

JAMES W. WOOLLEY.
